UNITED STATES PATENT OFFICE.

JESSE J. QUERY, OF OSCEOLA, NEBRASKA.

CURRENT MOTOR.

Application filed June 1, 1920. Serial No. 335,679.

To all whom it may concern:

Be it known that I, JESSE J. QUERY, a citizen of the United States, residing at Osceola, in the county of Polk and State of Nebraska, have invented certain new and useful Improvements in a Current Motor, of which the following is a specification.

This invention relates to current motors.

The object of the invention is to construct

10 a sectional apparatus of this character to take power from streams, rivers, or any currents of waters and by adding units thereto increase the power to any desired extent, the power being transmitted for any use desired.

15 Another object is to so construct such an apparatus that any stream may be harnessed thereby without damming the stream and any desired number of units used without one interfering with or decreasing the efficiency 20 of the others, on the contrary rather increasing their efficiency by promoting speed and depth of currents.

Another object is to so construct such a 25 motor that it may be made in all sizes, both lefts and rights, operating with efficiency from either bank and which runs at an angle oblique to the normal course of the stream, or other current of water, in connection with which it is to be used.

30 Another object is to so construct such a motor that it will be buoyant and thereby require less powerful construction to retain it in proper position for best service; is steady in its pull; and normally directs currents to the center of the stream; but may be used to direct them against either bank for washing away the bank and straightening irregular streams.

Another object is to provide a motor of 40 this character which will rid itself of all ordinary foreign bodies owing to its angular position by taking such bodies under and away with the current and which requires a minimum amount of attention after it is once 45 installed.

With the foregoing and other objects in view, which will appear as the description proceeds, the invention resides in the combination and arrangement of parts and in the 50 details of construction hereinafter described and claimed, it being understood that changes in the precise embodiment of the invention herein disclosed may be made within

the scope of what is claimed without departing from the spirit of the invention. 55

In the accompanying drawings:—

Figure 1 represents a top plan, partly in section, of a motor constructed in accordance with this invention.

Figure 2 is a diagrammatic view showing 60 one method of installing the motor constituting this invention.

Figure 3 is a similar view showing another mode of installing, and

Figure 4 is a similar view showing still 65 another mode.

In the embodiment illustrated a shaft 1 is shown mounted at its opposite ends in roller bearings 2.

The roller bearings 2 are mounted in suitable castings 7, water tight, and the rollers thereof are designed to turn in oil. The castings of these bearings have laterally extended spaced wings of flanges 7^a projecting in opposite directions from the rear of the 75 castings 7 and which are adapted to slide in suitable guides 8, carried by opposed faces of the piles 5, (see Fig. 1.)

It is obvious that the casting 7 can be 80 slid on the guide base, to adjust the position of the shaft 1 in the water.

Mounted on the shaft 1 between the piles 5 is a double cone-shaped buoyant member 10, fixed to said shaft and composed of two cone-shaped sections 11 and 12 with their 85 large ends abutting and connected water tight in any suitable manner shown at 13.

A plurality of bracing spiders 12^a connect the members 11 and 12 with the shaft 1 as is shown clearly in Fig. 1. These braces 90 vary in diameter to conform to the shape of the portion of the cone in which they are mounted and they operate not only to connect the cone with the shaft but to prevent its collapse under pressure. This cone 10 is 95 composed preferably of heavy strain resisting material and its opposite ends are equipped with water tight closures 10^a to prevent all possibility of water entering the cone which is designed to be buoyant to regulate the motor to proper depth automatically with the rise and fall of the stream in which it operates. 100

Secured to the outer faces of the cones 11 and 12 are wings 14 and 15, the wings on one 105 cone corresponding in number to those on

the other cone and each wing is spirally mounted on its cone, the wings on the rear cone 11 aligning with the corresponding wings on the front cone 12, so that the two alining wings when properly mounted will make an approximately half turn around the two cones. The combined wings which may be secured to the cones in any suitable manner form a spiral extending in the same direction. This peculiar mounting and shape of the wings 14 and 15 prevents water being carried up by the wings which would operate to kill the power of the motor, said wings being somewhat in the shape of a mold board of a plow.

The end of shaft 1 which projects toward the bank of the stream is mounted in a bearing in one wall of a boxing 17 and carries a bevel gear 18 which permits power to be transmitted from the power from shaft 1 to any other point where it may be required. This boxing 17 is made water tight and oil tight and the gears contained therein are designed to run in oil.

The other end of shaft 1 is equipped with a knuckle or universal joint 21 to provide for the movement of this end of the shaft when the motor is raised or lowered on the piles 5 without interfering with another shaft which may be connected therewith.

In Fig. 1 a double section or unit is shown but it is to be understood that any desired number of these units may be employed and connected by universal joints 21 to provide for their arrangement in streams of different widths and for increasing the power to be transmitted from the motor.

At the end of each section or unit are supports 5 here shown in the form of piles composed of any suitable material.

From the above description it will be obvious that by making this improved motor in sections or units and combining the units to obtain the power required an almost unlimited amount of power will be obtained and any river or stream with a fair volume of flow may be harnessed by such motor and the water or current used repeatedly.

Each unit of the motor will ordinarily be submerged a little more than one half but it is to be understood that the position of the unit may be regulated to place it at a point where most power is obtained.

By placing the units at an oblique angle in streams of running water the motor will be effectively operated without damming the stream and this position will adapt the motor to rid itself of all ordinary foreign bodies by taking them under and away with the current, therefore the angle in which the units are placed is held to be an essential feature of the invention, the peculiar construction of the wings being especially adapted for this peculiar positioning.

It is to be understood that the middle por-

tion of each unit 10 is of sufficient size to give just enough buoyancy to carry the unit to a proper depth, the construction to be enlarged according to the weight of the shaft, bracing spiders etc. The lifting capacity of each unit will have to be arranged by measurement, the size of the cones being regulated to suit conditions being made larger where the shaft 1 is increased in size and a larger load is to be carried thereby.

In Fig. 1 a direction changer is shown at 25 into which two wings carrying shafts 1 enter a casing 26 at an oblique angle, the case being here shown rectangular and the shafts entering through adjacent corners 80 mounted on roller bearings 2 and having intermeshing bevel gears 27, whereby the power from one shaft is transmitted to the other and the direction thereof changed.

In Fig. 2 is shown a diagrammatic view in which two series of connected units converge toward the center of the stream, the series being connected by a direction changer such as that shown at 25 in Fig. 1.

In Fig. 3 a multiplicity of series of units 90 are connected and arranged so as to obtain increased power which may be transmitted for any use desired.

In Fig. 4 a diagrammatic view is shown with the series of units inclining obliquely 95 from the banks from toward the center of the stream and spaced apart at the center of the stream.

Having thus described the invention, what is claimed as new and desired to be secured by Letters Patent, is:—

1. A water power device comprising a cone-shaped body portion, and a plurality of bent blades secured to the sides of the body to extend diagonally of the same, the corresponding ends of the blades being arranged in close proximity adjacent the apex of the conical body, and the opposite correspondingly ends of the blades being bent inwardly of the spaces between the blades and spaced a substantial distance apart to permit outlet of the water passing through the ways.

2. A water power device comprising a conical body, a plurality of bent blades secured by their edges to the body to extend diagonally across the same, the forward ends of the blades being relatively narrow and fastened adjacent the apex of the conical body, and the rear ends of the blades being flared to form relatively wide blades, and said ends being curved toward the succeeding blades and gradually tapered to permit free escape of water from the ways formed between the various blades.

3. A water power device comprising a body tapered from its intermediate portion toward its ends whereby the ends of the body are cone-shaped, and a plurality of peripheral blades secured to each end of the

body and arranged diagonally thereof, the blades at one end of the body being arranged in alinement with those at the opposite end thereof to form diagonally extending channels through the body.

4. A water power device comprising a body tapered toward the ends thereof from the intermediate portion in order to provide the body with conical ends, a plurality of 10 blades secured to opposite ends of the body

to extend diagonally thereof, and the ends of the blades on one end of the body being reduced in width adjacent the intermediate portion of the body.

In testimony whereof I affix my signature 15 in presence of two witnesses.
